(57) **CLAIM**

The ornamental design for a plumbing enclosure, as shown and described.

DESCRIPTION

FIG. 1 is a left, top, front perspective view of a plumbing enclosure embodying our new design;

FIG. 2 is a front elevational view thereof;

FIG. 3 is a right side elevational view thereof, the left side elevational view being a mirror image of the right side shown;

FIG. 4 is a top plan view thereof;

FIG. 5 is a cross-sectional view thereof taken along 5—5 of FIG. 2; and,

FIG. 6 is a cross-sectional view thereof taken along line 6—6 of FIG. 2.

The broken line representations of a drain in FIGS. 1, 3, 5 and 6, and of a shelf, a bar, and hardware in FIGS. 2 and 6, are for the purpose of illustration only, and form no part of the claimed design.
